SOLE PRESSING MACHINE

Fred L. Mconey, Lynn, Mass., assignor to United
Shoe Machinery Corporation, Paterson, N. J.,
a corporation of New Jersey

Application November 10, 1932, Serial No. 642,067

22 Claims. (Cl. 12—127)

This invention relates to sole pressing machines and more particularly to means for supporting boots or shoes for the sole pressing operation, and is illustrated herein as embodied in a machine of the type disclosed in Letters Patent of the United States No. 1,549,243 granted August 11, 1925 on an application of E. E. Winkley. Machines of that type comprise a sole pressing member or pad arranged to apply pressure to the bottom of a boot or shoe on a last and a jack for supporting the boot or shoe against the pressure of the pad.

It is an object of the present invention to provide in a sole pressing machine an improved jack on which a long legged boot may be readily mounted without the necessity of distorting the long leg of the boot to avoid interference with the sole pressing pad. With this object in view a feature of the invention, in one aspect, consists in a novel organization comprising, in combination with a sole pressing pad, a jack having members for supporting a boot or shoe at the heel end and forwardly of the heel end against the pressure of the pad, the heel end member being displaceable in a novel manner relatively to the other member and the pad to facilitate the mounting of a boot thereon.

In the illustrated construction the jack is provided with a pair of arms arranged respectively to support the heel end and the forepart of the boot or shoe against the pressure of the pad, and in order that a long legged boot may be readily mounted on the jack the heel end supporting arm is mounted to swing obliquely forward toward the operator and away from the forepart supporting arm into position to permit the operator to mount the boot thereon without distorting the leg of the boot and then to swing reversely to carry the boot into operative relation to the forepart supporting arm and the pad without interference between the boot and the pad. As shown there is provided friction means for holding the heel end supporting arm in work receiving position and also means for limiting its swinging movement into position to support the boot against the pressure of the pad.

In order that the jack may be adapted to support both long-legged boots and also shoes of widely varying sizes mounted on lasts of different heights, there is provided in accordance with a further feature of the invention, novel means constructed to permit the heel end support to be adjusted heightwise of the boot or shoe to accommodate the jack to lasts of different heights. In the construction shown, the heel end supporting arm is formed in two parts which are relative-

ly adjustable heightwise of the boot or shoe to vary the length of the arm in accordance with differences in the heights of different lasts, means being provided for locking the two parts of the arm against relative displacement from adjusted 5 relation in response to pressure of the pad on the sole. In view of the fact that the jack is thus adapted to support both boots and shoes, the term "shoe" is frequently used hereinafter for convenience as applicable to both kinds of foot- 10 wear.

The above and other features of the invention together with various novel details of construction and combinations of parts will now be more particularly described by reference to the accompanying drawings and will be pointed out in the claims. 15

In the drawings,

Fig. 1 is a view in front elevation of as much of a machine of the type illustrated in the above- 20 mentioned Letters Patent as is necessary to refer to for an understanding of this invention with novel features of the invention embodied therein; and

Fig. 2 is a plan view of parts shown in Fig. 1. 25

The present invention is illustrated as embodied in a sole-pressing machine of the type shown in the above-mentioned Letters Patent to which reference may be had for a more detailed description of the construction, arrangement and 30 operation of parts not fully described herein. The machine is provided with a pair of upwardly extending rods 10 on which there is adjustably secured a casting 12 for supporting a pair of downwardly extending arms or posts 14, 16, of a shoe- 35 supporting jack. The arm 14 which, as shown, is of sufficient length to receive a long-legged boot is provided at its lower end with a pin 18 for engaging the heel end of the last in its spindle hole, and the arm 16 is provided with a forked lower 40 end 20 in which there is secured a shaft 22, upon which shaft there is loosely journaled a roll 24 for engaging the forepart of a shoe. Mounted for sliding movement on the rods 10 is a carrier 26 provided with means at its opposite sides for sup- 45 porting a pair of trunnions, such as that indicated at 28, fast to a pad box 30 on which there is mounted a resilient sole-pressing form or pad 32 the upper surface of which is shaped to conform sub- 50 stantially to the longitudinal and transverse curvatures of the bottom of a shoe on the jack. In the illustrated machine the carrier 26 is moved toward and from the shoe-supporting jack by suitable power-driven mechanism which is not shown or described herein but is fully illus- 55

trated and described in the above-mentioned Letters Patent. It will be understood that the shoe is mounted on the jack by the operator when the carrier 26 and the pad 32 are in their lowermost 5 positions and that in the operation of the machine the pad is moved upwardly to apply pressure to the shoe before the machine comes to rest.

The heel pin 18 is supported on a holder 34 which is pivotally mounted at 36 on the arm 14, 10 and the holder 34 is controlled by a spring 38 which tends to tip the pin 18 toward the roll 24. When the last is mounted on the pin 18 the spring 38 accordingly tends to hold the forepart of the shoe pressed against the roll 24, thus assisting in 15 maintaining the shoe in the proper position for pressure to be applied to the shoe bottom by the upwardly moving pad 32.

In order that a long-legged boot may be readily mounted on the jack without bending or folding 20 over the long leg of the boot, the arm 14 is pivoted at its upper end so that it may be swung outwardly into a convenient position to receive the boot. As shown, the upper end of the arm is forked to straddle a boss 40 which is formed on a carrier 25 block 42 slidably mounted on a plate 44 which is secured to the support 12. Extending through the boss 40 and the arms 46, 48 of the forked upper end of the arm 14, is a shaft 50 which is held 30 against rotation in the boss 40 by a pin 52. Machines of the type illustrated in the Letters Patent referred to above are usually provided with 35 duplicate sole-pressing mechanisms whereby one shoe is subjected to pressure simultaneously with the release from pressure of another shoe previously operated upon. In order that the arm 14 may be swung outwardly into a convenient position to permit a boot to be mounted thereon and then inwardly to bring the forepart of the boot beneath the forepart supporting roll 24 without 40 interfering with the jack of the other twin mechanism or the uprights 10, the shaft 50 is so disposed that its axis extends in a direction inclined to the long axis of the boot or shoe.

Thus the arm 14 as it moves outwardly has components of movement longitudinally and laterally of the sole-pressing pad so that it swings from a substantially vertical position obliquely forward toward the operator and away from the forepart-supporting arm 16 into an inclined position to 45 receive a long-legged boot without interfering with the jack of the other twin mechanism or the uprights 10. Moreover, it will be seen that since the arm 14 is pivoted at its upper end for swinging movement in a vertical plane, it may be swung 50 into and out of operative relation to the arm 16 and the pad 32 without interference between the boot and the pad.

For holding the arm 14 in work-receiving position, while a boot is being mounted thereon 60 by the operator, there is provided friction means comprising a pair of friction disks 54, 56, the disk 54 being secured to the flanged end 58 of the arm 46 and the disk 56 to a sleeve 60 mounted on the shaft 50 (Fig. 2). The sleeve 60 is counterbored 65 to receive a spring 62 which tends to hold the friction disks 54, 56 in engagement with each other and the tension of which may be regulated by a nut 64 which is threaded on the rod 50. For holding the sleeve 60 and the friction disk 56 against 70 rotation, as the arm 14 is swung into and out of operative relation to the arm 16 and the pad 32, there is provided a pin 66 which is mounted in the sleeve 60 and extends through an aperture formed in the nut 64. A locknut 68 is provided for holding the nut 64 in adjusted position. The carrier

block 42 is provided with an abutment shoulder 70 arranged to engage a similar shoulder 72 formed on the arm 14 and to serve as a stop for the latter when it is swung inwardly to bring the forepart of the shoe beneath the forepart- 5 supporting roll 24.

The arms 14, 16 of the shoe-supporting jack are movable rectilinearly toward or from each other along the plate 44. In order to adjust them toward or from each other to accommodate 10 the jack to shoes of different lengths, there is provided a lever 74 which is fulcrumed at 76 to the support 12 and is provided with a downwardly extending arm 78 connected by a link 80 to the arm 16 and an upwardly extending arm 15 82 connected by a link 84 to the carrier block 42. The lever 74 is provided with a handle 86 which extends outwardly into a convenient position to be grasped by the hand of the operator and by means of which the operator may swing the lever 20 74 about its fulcrum 76 to move the arms 14, 16 toward or from each other.

In the illustrated machine the arm 14 comprises two parts relatively adjustable heightwise of the shoe to accommodate the jack to lasts of 25 different heights. As shown particularly in Fig. 1 the arm includes a lower portion 88 and an upper portion 90 which is bifurcated to receive the lower portion 88 and is provided with a pin 92 which extends through a lengthwise slot 94 30 formed in the lower portion. The two parts of the arm are thus relatively adjustable heightwise of the shoe to vary the length of the arm to compensate for differences in the heights of different lasts. In order that the lower part 88 35 of the arm may be held in any one of a plurality of adjusted positions, it is provided with a series of grooves 96 which are spaced apart heightwise of the arm 14 and any one of which may receive a pin 98 carried by the upper portion 90. 40 By this pin and groove construction the two parts of the arm are accordingly locked together against relative upward or downward movement. To prevent them from becoming unlocked the upper portion 98 is provided with a lengthwise 45 slot 100 in which there is slidably mounted a pin 102 carrying a roll 104. The roll 104 is arranged to engage an inclined surface 106 formed on the upper end of the lower portion 88 of the arm. It will be readily seen that after moving the roll 104 50 upwardly out of engagement with the inclined surface 106 the lower portion 88 may be swung about the pin 92 and raised or lowered as desired, and may then be swung into interlocking 55 relation with the pin 98, after which the roll 104 may be moved downwardly into engagement with the inclined surface 106 to hold the upper and lower portions of the arm against displacement from adjusted relation.

Having thus described my invention, what I 60 claim as new and desire to secure by Letters Patent of the United States is:—

1. In a sole-pressing machine, the combination with a sole-pressing pad shaped to conform substantially to the longitudinal and transverse 65 curvatures of the bottom of a boot on a last, of a jack for supporting the boot and last for the sole-pressing operation comprising a support for the heel end of the boot and a support for the boot forwardly of the heel end, said heel end support being displaceable from shoe-supporting position laterally of the pad relatively to said other support to facilitate the mounting of each boot thereon.

2. In a sole-pressing machine the combination 75

- with a sole-pressing member, of a jack for supporting a boot and last for the sole-pressing operation comprising a support for the heel end of the boot and a support for the boot forwardly of the heel end, said heel end support being displaceable from shoe-supporting position laterally of the boot relatively to said other support to permit each boot readily to be mounted thereon.
5. In a sole-pressing machine, the combination with a sole-pressing pad shaped to conform substantially to the longitudinal and transverse curvatures of the bottom of a shoe on a last, of a jack for supporting the shoe and last against the pressure of the pad comprising a pair of supports arranged respectively to support the heel end and forepart of the shoe, said heel end support being movable relatively to the forepart support into a position with its shoe-receiving portion removed from over the pad to receive each shoe and then into position to support the shoe against the pressure of the pad with the forepart of the shoe in engagement with the forepart support.
10. 3. In a sole-pressing machine, the combination with a sole-pressing pad shaped to conform substantially to the longitudinal and transverse curvatures of the bottom of a shoe on a last, of a jack for supporting the shoe and last against the pressure of the pad comprising a pair of supports arranged respectively to support the heel end and forepart of the shoe, said heel end support being mounted to swing laterally of the shoe relatively to the forepart support into position to receive a shoe and then to swing reversely to carry the boot into operative relation to the other supporting member and the pad.
15. 4. In a sole-pressing machine, the combination with a sole-pressing pad shaped to conform substantially to the longitudinal and transverse curvatures of the bottom of a shoe on a last, of a cooperating shoe-supporting jack comprising members arranged respectively to support the forepart and heel end of the shoe, said heel end supporting member being mounted to swing outwardly relatively to the forepart supporting member into a position with its shoe-receiving portion removed from over the pad to receive each shoe and then inwardly into position to support the shoe against the pressure of the pad with the forepart of the shoe in engagement with the forepart supporting member.
20. 5. In a sole-pressing machine, the combination with a sole-pressing member for applying pressure to the bottom of a shoe on a last, of a jack for supporting the shoe and last against the pressure of said member comprising a pair of supports arranged respectively to support the heel end and forepart of the shoe, said supports being interconnected for simultaneous movement toward or from each other in directions lengthwise of the shoe, and said heel end support being movable relatively to the forepart support into position to receive each shoe and then into position to support the shoe with the forepart of the shoe in engagement with the forepart support.
25. 6. In a sole-pressing machine the combination with a sole-pressing member, of a jack for supporting a boot and last against the pressure of said member comprising members for supporting the boot at the heel end and forwardly of the heel end, said heel end supporting member being movable lengthwise of the boot away from said other supporting member with a component of movement laterally of the sole-pressing member into position to permit the operator to mount each boot thereon without interference between the boot and the sole-pressing member.
30. 7. In a sole-pressing machine the combination with a sole-pressing member, of a jack for supporting a boot and last against the pressure of said member comprising members arranged respectively to support the boot at the heel end and forwardly of the heel end, said heel end supporting member being mounted to swing diagonally forward and to one side with respect to the operator's working position to permit the operator readily to mount the boot thereon.
35. 8. In a sole-pressing machine the combination with a sole-pressing pad, of a jack for supporting a boot and last against the pressure of said pad comprising members for supporting the boot at the heel end and forwardly of the heel end respectively, said heel end supporting member being mounted to swing obliquely forward toward the operator and away from the other supporting member into position to receive the boot without interference with the pad and then to swing reversely to carry the boot into operative relation to the other supporting member and the pad.
40. 9. In a sole-pressing machine, the combination with means for applying pressure to the bottom of a shoe on a last, of a jack for supporting a shoe and last against said pressure comprising a pair of supports arranged respectively to support the heel end and forepart of the shoe, said heel end support being mounted to swing laterally of the shoe relatively to the forepart support into position to receive a shoe and then to swing reversely to bring the forepart of the shoe into engagement with the forepart support, and a stop carried by said heel end support for limiting its swinging movement.
45. 10. In a sole-pressing machine the combination with a sole-pressing pad, of a jack for supporting a long-legged boot against the pressure of said pad comprising members arranged respectively to support the boot bottom downward at the heel end and forwardly of the heel end, said supporting members being movable rectilinearly toward or from each other to accommodate shoes of different sizes, and said heel end supporting member being pivoted at its upper end above the leg of the boot so that it may be swung relatively to the pad to receive the boot.
50. 11. In a sole-pressing machine, the combination with a sole-pressing pad, of a jack for supporting a long-legged boot against the pressure of said pad comprising a forepart support and a support for the heel end of the boot, said forepart and heel end supports being mounted for bodily movement toward or from each other lengthwise of the shoe, and said heel end support being mounted for swinging movement in a plane inclined to the direction of its movement lengthwise of the shoe to permit its shoe receiving end to be moved away from the pad to receive the boot and toward the pad to move the forepart of the boot into engagement with the forepart support without interference between the boot and the pad.
55. 12. In a sole-pressing machine the combination with means for applying pressure to the bottom of a shoe on a last, of a jack for supporting the shoe and last bottom downward against said pressure comprising members for supporting the shoe at the heel end and forwardly of the heel end respectively, said members being interconnected for simultaneous movement toward or from each other lengthwise of the shoe, and said heel end supporting member being mounted independently to swing inwardly and outwardly about an axis located above the shoe to carry the shoe into and out of operative relation to the other supporting member and the sole-pressing means.
60. 13. In a sole-pressing machine, the combination with means for applying pressure to the bottom of a shoe on a last, of a jack for supporting the shoe and last bottom downward against said pressure comprising arms arranged respectively forward and to one side with respect to the operator's working position to permit the operator readily to mount the boot thereon.

- to support the forepart and heel end of the shoe, said heel end supporting arm being mounted to swing outwardly into position to receive the shoe, and friction means for holding said arm in shoe-receiving position.
5. 14. In a sole-pressing machine the combination with a sole-pressing pad, of a jack for supporting a shoe and last against the pressure of said pad comprising a forepart support and a heel end support, said heel end support being mounted to swing from a substantially perpendicular position with respect to the pad into an inclined position with respect thereto to receive a shoe, and a friction device for holding said heel end support in any inclined position into which it may be moved.
10. 15. In a sole-pressing machine, the combination with a sole-pressing pad, of a jack for supporting a long-legged boot bottom downward against the pressure of said pad comprising arms arranged respectively to support the forepart and heel end of the boot, said heel end supporting arm being mounted for swinging movement in a vertical plane to permit its lower end to be moved away from the pad to receive the boot and toward the pad to move the forepart of the boot beneath the forepart support without interference between the boot and the pad, and a stop for limiting the swinging movement of said 15 arm toward the pad.
15. 16. In a sole-pressing machine the combination with a sole-pressing pad, of a jack for supporting a long-legged boot against the pressure of said pad comprising arms arranged respectively to support the boot at the heel end and forwardly of the heel end, said heel end supporting arm being mounted to swing outwardly into position to receive the boot and then inwardly to carry the boot into operative relation to the other support and the pad without interference between the boot and the pad, friction means for holding the heel end supporting arm in position to receive the boot, and a stop for limiting its inward swinging movement.
20. 17. A sole-pressing machine having, in combination, a sole-pressing pad, a jack for supporting a shoe and last against the pressure of said pad comprising arms arranged respectively to support the forepart and heel end of the shoe, means for adjusting the forepart and heel-end supporting arms bodily toward or from each other in directions lengthwise of the shoe to accommodate the jack to shoes of different lengths, said heel-end supporting arm being formed in two parts constructed to interlock with each other in any one of a plurality of predetermined positions to vary the length of the arm to accommodate lasts of different heights, and means for holding the two parts of the arm in interlocked relation.
25. 18. In a sole-pressing machine, the combination with a sole-pressing form arranged to apply sole-shaping pressure to the bottom of a shoe on a last, of a jack for supporting the shoe and last for the sole-pressing operation comprising arms arranged respectively to support the forepart and heel end of the shoe, said heel end supporting arm being formed in two parts constructed to interlock with each other against relative heightwise movement in either direction in any one of a plurality of predetermined positions to vary the length of the arm to accommodate lasts of different heights.
30. 19. In a sole-pressing machine, the combination with a sole-pressing pad, of a jack for supporting a shoe and last against the pressure of said pad comprising a forepart-supporting arm and an arm for supporting the heel end of the shoe, said heel end supporting arm being movable independently of the forepart supporting arm into position to receive each shoe and being formed in two parts relatively adjustable heightwise of the shoe, and means for locking the two parts of the arm against relative displacement from adjusted relation in response to pressure applied to the sole.
35. 20. In a sole-pressing machine, the combination with a form for applying sole-shaping pressure to the bottom of a shoe on a last, of a jack for supporting the shoe and last against said pressure comprising a forepart-supporting arm and an arm for supporting the heel end of the shoe, said heel end supporting arm having an upper portion and a lower portion relatively adjustable heightwise of the shoe and constructed to interlock with each other in any one of a plurality of predetermined positions through relative lateral movements of said upper and lower portions, and means for holding the upper and lower portions of the arm in interlocked relation.
40. 21. A sole-pressing member having, in combination, means for applying pressure to the bottom of a shoe on a last, a jack for supporting the shoe and last against said pressure comprising a forepart-supporting post and a two-part heel post the parts of which are relatively adjustable heightwise of the shoe, one of said parts being provided with a pin arranged to enter any one of a series of grooves formed in the other part to lock the two parts of the heel post against relative upward or downward movement from adjusted relation, and means for holding the two parts of the heel post in interlocked relation.
45. 22. A sole-pressing machine having, in combination, means for applying pressure to the bottom of a shoe on a last, a jack for supporting the shoe and last against said pressure comprising a forepart-supporting post and a two-part heel post the parts of which are relatively adjustable heightwise of the shoe, one of said parts being provided with a series of grooves spaced apart heightwise of the heel post, a pin carried by the other part and arranged to enter any one of the grooves to lock the two parts of the heel post against relative upward or downward movement from adjusted relation, and a roll carried by one of the parts adjustable heightwise of the heel post and arranged to engage an inclined surface formed on the other part to prevent unlocking of the two parts of the heel post.

FRED L. MOONEY. 65
